UNITED STATES PATENT OFFICE.

JOHN KNAPP, OF HOLLAND, MICHIGAN.

MOLDING-MACHINE.

1,339,354.

Specification of Letters Patent.

Patented May 4, 1920.

Application filed April 2, 1919. Serial No. 286,859.

To all whom it may concern:

Be it known that I, JOHN KNAPP, a citizen of the United States, residing at Holland, in the county of Ottawa and State of Michigan, have invented certain new and useful Improvements in Molding-Machines, of which the following is a specification.

The present invention comprehends generally improvements in that class of inventions known as metal founding and more particularly relates to an improved molding apparatus.

This invention has for its principal object to provide a device of the above mentioned character the construction of which is an improvement over that covered in my previous Patent No. 1,273,649 dated July 23rd, 1918, and embodies generally an improved or rearrangement of the manually operable mechanism for independently or collectively moving the supporting table and the flask supporting means.

It is an additional and equally important object of this invention to provide an apparatus of the above mentioned character wherein the operating handle of the table moving means is fitted with a weight which acts to automatically raise the table when the flask supporting means is in a raised position, the flask being so associated with the table, that when the moving means is operated the table will be moved to a lowered position and will remain in such position when the flask is being filled with molding material.

The invention also embraces the provision of a molding apparatus of the above mentioned character wherein plates are adjustably mounted within the supporting casing or sleeve so as to be moved laterally inwardly to coact with the adjacent face of the supporting stem of the table and as a result compensate for wear on these parts which is incident to a continuous use thereof, in consequence obviating any play between these parts which would have a tendency to interfere with the production of an effective mold.

It is another object of this invention to provide a molding apparatus of the above mentioned character wherein auxiliary supporting means is employed for removably retaining the secondary or swinging frame which serves as a supporting means for the flask positively spaced above the table at

the time the finished mold is being removed from the flask, additional and adjustable supporting means being incidentally employed for supporting the pattern slightly spaced from the cover plate which rests on the table, allowing a slight drop of the mold from the pattern and in consequence facilitating the subsequent removal of the pattern.

The invention has for another object to provide a molding apparatus of the above mentioned character wherein coöperative catch means is mounted on the platform of the frame or carriage and on the handle which moves the table for releasably retaining the handle and consequently the table in various positions of adjustment.

It is another object of this invention to provide a molding apparatus of the above mentioned character wherein coöperative means is mounted on the flask and on the secondary swinging frame which supports the flask for releasably holding the flask in an inverted position and the catches in a raised position at the time the flask is raised and while one of the molds is being removed from the pattern.

More specific objects of this invention consist in the provision of handles on the pattern to facilitate the handling thereof; to provide a movable catch bar on one of the bearing standards for removable association with the operating handle of the moving means for the flask supporting means, and to provide improved means for mounting the carriage.

Among the other aims and objects of this invention may be recited the provision of an apparatus of the above mentioned character which is comparatively simple in construction, durable and one which will be very efficient in use and operation.

The improvements in the details and arrangement of parts will be apparent from an inspection of the accompanying drawings, in connection with the specific description hereinafter contained, and wherein the preferred embodiment of the invention is disclosed for the purpose of imparting a full understanding of the invention.

The invention is clearly illustrated in the accompanying drawings, in which:

Figure 1 is a side elevation of the improved molding apparatus,

Fig. 2 is a top plan view thereof,

Fig. 3 is a transverse sectional view through the apparatus showing the position assumed by the flask when the mold is being removed from the pattern.

5 **Fig. 4** is a fragmentary elevational detail of the means for releasably holding the flask in an inverted position when raised.

Fig. 5 is a transverse horizontal sectional view taken on line 5—5 of Fig. 3, and

10 **Fig. 6** is a side elevational detail of the means for releasably maintaining the operating handle for the table in various positions of adjustment.

Fig. 7 is a perspective view of the pin or **15** pluck removed.

Similar characters of reference are employed in all of the above described views, to indicate corresponding parts.

Referring now, more particularly, to the **20** accompanying drawings there is provided a carriage designated in its entirety by the numeral 1 consisting of a frame 2 the forward and the rear ends of which are journaled axles 3, the forward axle being fitted **25** with spaced supporting wheels 4 near its respective ends while the rear axle is fitted with a single supporting wheel or roller 5 medially of its ends, the said wheels 4 and **5** operating on suitable tracks so that the **30** molding apparatus will be transported from place to place during the molding process.

Spaced standards 6 rise from the frame 2 near the forward extremity and are connected by a cross bar 7 which is provided **35** with a central square opening 8 while secured to the cross bar near the respective ends are plates 9 formed with transverse slots 10 in which are pivotally mounted the lower ends of supporting pins 11, the upper **40** ends of which are adjustably fitted with vertically movable screws 12 for a purpose which will presently appear. A table 13 is arranged above the cross bar the opposite side edges being provided with spaced slots **45** 14 for disposition about the guide and supporting pins 11 while depending centrally from the under surface of the table is a squared shank or stem 15 which is arranged through the opening 8 in the cross bar and **50** accommodated within the squared sleeve 16 carried with and depending from the cross bar and alining with the opening 8. The opposite sides of the casing at the lower edge are provided with opposed vertical **55** slots 17 while arranged transversely through the lower projecting portion of the shank 15 is an axle 18 upon which are rotatably mounted rollers 19 and with which coact cams 20 which project in turn from a transverse shaft 21 rockably mounted in the frame 2. An operating handle 23 is connected to one end of the shaft, the upper portion being offset as at 23' and is fitted at its outer end with a weight 24 which **65** normally acts to cause the cam 21 to bear

against the rollers 20 and in consequence hold the table in a raised position, that is, when no weight is disposed on the table.

As the shank and sleeve are subjected to a wearing action wear plates 25 are arranged **70** between the inner surfaces of certain walls of the casing or sleeve 16 and the adjacent faces of the shank 15 being adjustable toward the shank to compensate for the wear by suitable adjustable elements such as **75** screws 26 and by this peculiar arrangement of parts it is apparent that play between the parts will be obviated.

As intimated, an improved flask generally designated by the numeral 27 has been employed and in the present instance consists of a substantially square receptacle 28 having inclined walls from the opposite sides of which project trunnions 29. The upper edges of the walls are provided with outwardly directed horizontal flanges 30 to which are slidably connected retainers 31 the outer edges of which are in turn formed with finger pieces 32 to facilitate sliding thereof. The pattern 33 may be of any **90** conventional shape and consists of a frame 34 to which is connected a longitudinally curved bottom piece 35 while between the frame and the edges of the bottom are the side pieces 36. Handles 37 are connected **95** to the side edges of the flanged portions of the frame and these flanged portions are also provided with openings 38 designed for engagement with the vertically arranged guide pins 39 which project from the side **100** flanges 30 of the receptacle. A cover plate 40 is designed for association with the upper edge of the frame of the pattern while the parts are held together by hook-like catches **105** 40' pivoted as at 41 to the front and rear sides of the receptacle.

As intimated, improved means has been provided for supporting and moving the flask and in reducing this feature of the invention to practice, opposed vertical standards 42 rise from the frame 2 near the rear end thereof being braced by braces 43 while bearings 44 are adjustably connected for vertical movement at the upper ends of the standards and operably receive the ends of a transverse shaft 45 to which is connected the secondary frame 46 for the flask. This frame 46 consists of side bars 47 which are connected near their rear ends to the shaft **110** 45 and have their rear ends connected by a cross bar 48 for a purpose which will presently appear while the forward portions are offset as at 49 and the outer terminals of the offset portions of the side bars are provided with bearings 50 in which are removably journaled the trunnions 29 of the flask. A segmental gear 51 has its inner end connected to the shaft 45 and is also connected with the cross bar 47 being provided with internal teeth 52 near its outer edge with **120** **125** **130**

which meshes a pinion 53 carried by a shaft 54 in turn journaled in spaced bearing brackets 55 carried by one of the braces 43. A gear 56 is also mounted on the shaft 54 and is meshed by a pinion 57 carried by the inner end of a stub-shaft 58 while journaled in the adjacent standard 42 and the outer end of this stub-shaft 58 is fitted with a crank handle 59 which upon rotation is designed to swing the frame 46 in either direction to consequently raise and lower the flask with respect to the supporting handle. To facilitate movement of the segmental gear 51 in a direction to cause the elevation of the molding flask, a contractile coil spring 60 is employed and has one end connected to the segmental gear as at 61 and extends diagonally therefrom, the opposite end being connected as at 62 to the squared sleeve or casing 16. A weight 60' is also connected to the gear 51 to further facilitate the elevation of the molding flask.

In order to releasably hold the receptacle 27 of the flask in a raised and inverted position at the time the mold is being removed from the pattern 33, a catch bar 63 is pivoted to the outer end of an arm 64 which depends at right angles from one of the side bars 47 of the frame 46 near the offset portion thereof and the outer end of the latch bar is designed to be arranged between spaced ears 65 which project laterally from the front face of the receptacle 28 near the lower edge thereof. A set-screw 66 is mounted in one of the ears and is designed to clamp the bar 63 thereto. In addition the bar 63 carries a laterally disposed keeper 67 designed to releasably hold the adjacent hook-like catch in an inactive position, the particular arrangement of parts being shown in Fig. 4.

In order to retain the flask 27 and table 13 relatively stationary at the time it is desired to remove the mold from the receptacle 28 and subsequent to the removal of the pattern, struts 68 are pivoted to the outer ends of the cross bar 7 and are designed to be swung upwardly so as to be engaged by the under surfaces of the bearings 50 preventing a downward movement of the flask beyond the point of engagement. A shouledered element 70 is arranged to one side of the frame 2 in the rear of the shaft 22 which acts as a retainer being preferably right angular in cross section forming a lower shoulder 71 and an upper shoulder 72, while the upper surface of the element is also designed to act as a stop for a shoulder 73, the shoulders 71, 72 and 73 being designed to be engaged at times by a removable pin 74 which is arranged transversely through the inner portion of the handle 23, the particular engagement and advantages of this construction being hereinafter set forth.

At times, during the molding operation, it

is found necessary to prevent an accidental rotation of the crank handle and with this end in view a keeper or latch bar 75 is pivoted to one of the bearings 44.

During the formation of the mold in the pattern and in the receptacle, a pin or pluck 76 is adapted to be arranged centrally and vertically in the pattern and subsequently in the flask leaving an opening through the mold through which molten metal is adapted to be subsequently poured, as is apparent.

The mode of operation of the present invention may be reviewed as follows:—

Assuming that the parts have been assembled in the manner described and as shown in the drawings, the hook catches 40' are disengaged from the cover plate 40 whereupon sand is packed or rammed into the pattern 33, and subsequent to the packing of the sand the cover is positioned on the pattern and held by the catches 40'. The crank handle 59 is now engaged and partially rotated so as to raise the secondary frame 46 as well as the flask inasmuch as the mold in the pattern is heavier than the receptacle 28, the flask will automatically assume an inverted position whereupon the handle 59 is engaged so as to bring the flask into engagement with the supporting table 13. The pluck or pin 76 is now adapted to be inserted in the opening in the curved bottom 35 of the pattern whereupon the receptacle is filled with sand and rammed; subsequently to this latter action the pin 76 is removed leaving the opening therein. The struts 68 are now swung upwardly so that the bearings 50 will rest on the upper edges thereof and during this action the pivoted bar 63 will be engaged between the ears 65 and held in disengagement by the set-screw 66, the keeper bar 67 being arranged to engage the bill of the adjacent hook-like catch 40', which is previously released, so as to hold this catch in a position so that it will not interfere with the proper operation of the parts. In this connection it is to be particularly observed that the flask is now in a horizontal position. The pin 74 in the handle 23 is now released from its engagement with the upper shoulder 72 so that the handle 23 may be raised and the table 13 lowered carrying with it the cover plate 40 and the pattern 33. In this connection it is to be particularly observed that the flanged portion of the frame 34 of the pattern engages the adjustable screws 12 in the guide pins 11 so as to be held slightly spaced from the cover plate 40 which is on the table 13, this action causing the dislodgment of the mold from the pattern so that it will rest on the plate 40. Of course the mold does not become disengaged of itself, but a slight tapping of the pattern will cause such disengagement.

The handle 59 is now engaged and rotated to raise the flask into a relatively high position.

tion whereupon the keeper or catch 75 is moved outwardly to prevent accidental lowering movement of the flask. The handles 37 on the flanged portion of the frame of the pattern 33 are engaged so that the pattern may be lifted from the pins 11. The bar or keeper is now released and the handle engaged to move the flask downwardly until the bearings 50 rest upon the upper ends of the struts 68, being thereby prevented from having further downward movement. The handle 23 is now swung downwardly to raise the table 13 whereupon the pin 74 is engaged beneath the lowermost shoulder 71 so that regardless of any weight disposed on the table the same will be held in a raised position. As a result of this action, the mold in the flask and the mold on the table will be placed close together. The finger pieces 32 are now engaged to slide the retainers 31 from engagement with the mold and the receptacle 28. The pin 74 is now removed from the shoulder 71 and the handle 23 moved upwardly by imparting a slight upward pressure on one of the arms of the secondary frame. In other words, the weight of the mold on the table overcomes the action of the weight 24 in the handle 23 lowering the table and raising the handle automatically while simultaneously the action of the spring 60 and weight 60' on the empty receptacle automatically raises the flask or rather the receptacle thereof subsequent to the slight initial movement of the frame. The plate 40 which supports the molds is now removed from the table and after this action the bar 63 is disengaged from the ear 65 allowing the receptacle to right itself. When the molds are removed from the table the weight 24 acts to automatically raise the table and by replacing the pattern on the receptacle the molding operation may be repeated, as is apparent.

45 It is believed in view of the foregoing description that a further detailed description of the operation of the invention is entirely unnecessary. Likewise, it is believed that the advantages of the invention will be readily apparent.

As many changes could be made in the above construction and as many apparently widely different embodiments of this invention could be made without departing from the scope thereof, it is intended that all matter contained in the above description and shown in the accompanying drawings, shall be interpreted as illustrative and not in a limiting sense. It is also to be understood that the language used in the following claims is intended to cover all of the generic and specific features of the invention herein described and all statements of the scope of the invention, which as a mat-

ter of language, might be said to fall there-between.

Having thus fully described the invention, what is claimed as new and desired to be secured by Letters Patent, is:-

1. In molding apparatus, a supporting frame, spaced standards thereon, a cross bar connecting the standards, a squared sleeve depending from the cross bar, a table, a shank depending from the table, and vertically slidable through the sleeve, means for raising and lowering the table, and laterally adjustable wear plates connected to the inner faces of certain of the walls of the sleeve for coacting with the shank.

2. In molding apparatus, a supporting frame, spaced standards thereon, a cross bar connecting the standards, a squared sleeve depending from the cross bar, a table disposed on the cross bar, a shank depending from the table and vertically slidable through the sleeve, means for raising and lowering the table, wear plates arranged adjacent the inner surfaces of certain of the walls of the sleeve for coacting with the shank, and means for adjusting the plates relative to the shank.

3. In molding apparatus, a supporting frame, standards on said frame, a cross bar connecting the standards, a sleeve depending from the cross bar, a table disposed on the cross bar, a shank depending from the table and arranged through the sleeve, a shaft through the shank, rollers on the ends of the shaft, a transverse shaft in the frame, roller engaging cams projecting from the shaft, an operating handle connected to the shaft, and a weight connected to the outer end of the handle and acting to normally hold the table in a raised position.

4. In molding apparatus, a supporting frame, standards on said frame, a cross bar connecting the standards, a sleeve depending from the cross bar, a table disposed on the cross bar, a shank depending from the table and arranged through the sleeve, a shaft arranged through the shank, rollers on the shaft, a transverse shaft rockably mounted in the frame, roller engaging cams projecting from the shaft, an operating handle connected to the shaft, a weight connected to the outer end of the handle designed to hold the table in a raised position, a flask for association with the table, means on the frame for pivotally supporting and moving the flask vertically, and cooperative means on the handle and on the frame for releasably holding the table in various positions of adjustment regardless of the position of the flask.

5. In molding apparatus, a flask, means for pivotally supporting and moving said flask vertically, spaced ears on the flask, a bar pivotally connected with the flask sup-

porting means, and means for releasably clamping the bar between the ears when said supporting means is in a raised position.

6. In molding apparatus, a supporting frame, a flask, means for pivotally supporting and moving said flask vertically, means for operating said flask supporting means, means for releasably holding said operating means against movement when the flask is raised, coöperative means on said flask supporting means and on the flask for releasably holding the flask inverted when the flask supporting means is held in a raised position.

7. In molding apparatus a supporting frame, spaced standards thereon, a cross bar connecting said standards, a table, a shank depending from the table and slidably arranged through the cross bar, a rockably mounted transverse shaft in the frame, an operable connection between the shaft and

the shank and while the shank is rocked the table will be raised or lowered, a weighted handle connected to the shaft designed to normally hold the table in a raised position, 25 a flask, a secondary frame mounted on the main frame and designed for vertical swinging movement and for pivotally supporting the flask, struts pivoted to the cross bar designed to be swung upwardly at times to 30 limit the downward movement of the secondary frame, and coöperative means on the frame and on the handle for releasably holding the handle and consequently the table, against movement and in the proper 35 position to receive the mold from the flask at the time the secondary frame is supported by the struts.

In testimony whereof I affix my signature hereto.

JOHN KNAPP.
